(57) **CLAIM**

The ornamental design for a cut potato product, as shown and described.

DESCRIPTION

FIG. 1 is a top plan view of a cut potato product;

FIG. 2 is a bottom plan view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a perspective view thereof; and,

FIG. 8 is an opposite perspective view thereof.

The evenly-spaced broken lines shown in the drawings illustrate portions of the cut potato product that form no part of the claimed design. The dash-dot-dash broken lines in the drawings illustrate the boundary of the claimed design which forms no part thereof.
